(57) **CLAIM**

The ornamental design for a medical device, as shown and described.

DESCRIPTION

FIG. 1 is a perspective view of a medical device showing our new design;

FIG. 2 is a second perspective view of a medical device shown in FIG. 1;

FIG. 3 is a front view of the medical device shown in FIG. 1;

FIG. 4 is a rear view of the medical device shown in FIG. 1;

FIG. 5 is a side view of the medical device shown in FIG. 1;

FIG. 6 is a top view of the medical device shown in FIG. 1;

FIG. 7 is a perspective view of the medical device shown in FIG. 1;

FIG. 8 is a perspective view of the medical device shown in FIG. 1; and,

FIG. 9 is a perspective view of the medical device shown in FIG. 1.

Elements shown in evenly dashed broken lines show environmental structures and elements shown in evenly dashed broken lines show non-claimed portions of the medical device and form no part of our design.

1 Claim, 4 Drawing Sheets
